MENDING HOOK FOR STOCKINGS

Jeannette V. Maillet, Brownville Junction, Maine,
assignor of one-half to Philip J. Maillet,
Brownville, Maine

Application January 11, 1946, Serial No. 640,609

3 Claims. (Cl. 66—117)

1

My invention relates to a tool or mending hook for repairing runs in stockings or other similar knitted articles.

The main object of this tool is to facilitate the mending of a run in a stocking for instance and the tool consists of three main shanks secured together in a short handle, all making a very neat little tool or knitting hook.

In order to make the hook work as easily as possible it is advisable to stretch the article to be mended over a hard smooth surface. For this reason an ordinary drinking glass or a knitting ball should be inserted in the stocking and the torn part thereof stretched flat and smooth, without wrinkles over the smooth surface of the glass.

The uses and advantages of this tool will be understood from the following description with the aid of the attached drawing.

One embodiment of the invention is illustrated in the accompanying drawing in which

Figure 1 is a side elevation of the mending tool in about three times its natural size;

Figure 2 is a side elevation of the guard member;

Figure 3 is a side elevation of the needle proper;

Figure 4 is a similar fragmentary view of the hook member with latch;

Figure 5 is a top plan view of Figure 4;

Figure 6 is a cross section along line 6—6 of Figure 1.

Like reference numerals refer to the same parts in the different views.

As best seen in the assembled view, Figure 1, this tool or mending hook consists of a handle 10 in one end of which are inserted a hook shank or member 11, a spring shank or needle 12 and a guard 13, the parts 12 and 13 being gently arched towards the hook shank 11.

These three parts are all inserted and firmly secured together in a suitable hole bored in the handle 10 after first soldering together needle 12 and guard 13. As soon as the solder has set I attach hook shank 11 to the united parts 12 and 13 to form a unit which is then inserted and firmly secured by cement, for instance, in the handle 10.

The forward end of the hook member terminates with well rounded and turned back hook proper 14 and to the rear thereof is shown a vertical slot 15 in which is mounted to freely oscillate on a transverse pin 16, a pointed finger or latch 17 which is adapted to lie flat on the rear or inner end of hook 14 thus forming an eye 18 as clearly seen in Figure 4. An upright position

2

of the latch 17 is indicated by dotted lines in the same figure.

As seen in Figure 1 the guard 13 having its bottom surface wall rounded at 22 projects slightly with its sharp nose 20 beyond the hook portion 14 on hook member or shank 11 and the needle 12 reaches with its inturned sharp point 21 just beyond the pin 16 of the latch 17 as to cause the latch 17 to be thrown forward against the top of the hook 14. An eye as at 18 is thus provided between parts 14 and 17.

Likewise, there is always an open space 19 between the spring arm or needle 12 and the hook member 11 back of the hump for pin 16 thereon in which the pivot pin 16 is held, and where the shank 11 has a recess 23. From Figure 6 it will be seen that the hook shank 11 is located slightly to one side of the needle 12 and the guard 13.

The manner of operation in mending a torn stocking is the following.

First, insert a drinking glass or any other suitable object having a hard, smooth or polished surface into a stocking, pressing the injured portion thereof against the hard surface and stretch 25 the fabric thereover so that it becomes flat and straight.

Then allow the hook to engage the loop at the run in the stocking. By then placing the point 20 of the guard 13 in a new stitch and pushing 30 the hook member 11 into the stocking the thread will enter between the guard 13 and the spring arm or needle 12, and, when passing, this will raise the latch or finger 17 up to level of the spring arm or needle 12. Then the stitch which 35 is held in the hook 14 goes up high on the hook and enters the space 19.

By the operator then pulling the tool towards himself this will bring the thread down faster than the hook member 11 while the latch 17 still 40 remains raised and the thread at the latch 17 drops into the hook eye at 18.

Then the thread on hook 14 immediately drops down and while passing the latch 17 drives another thread into the hook eye at 18 and passes 45 it to the top.

It is to be understood that the invention as here disclosed is not limited to the details here described and shown but that the same may be varied without departing from the spirit of the 50 invention as defined by the subjoined claims.

I claim:

1. A mending tool for knitted fabric, comprising a handle and three forwardly protruding shanks rigidly secured therein, of which the middle shank constitutes a needle, the top shank

constitutes a guard for the needle both said shanks being gradually arched parallelly inwards and each terminating with a sharp point; the third of said shanks constitutes a backwardly bent, well-rounded hook, a latch finger pivoted rearwardly of said hook and adapted to rest with its pointed free end upon the rear end of said hook, thereby forming an eye therewith; said third shank having a recessed portion between the latch finger and the handle to provide an open space between said needle and the third shank.

2. A mending tool for knitted fabric, comprising a handle and three forwardly protruding shanks rigidly secured therein, of which the middle shank constitutes a needle, the top shank constitutes a guard for the needle both said shanks being gradually arched parallelly inwards and each terminating with a sharp point; the third of said shanks constitutes a backwardly bent, well-rounded hook, a latch finger pivoted rearwardly of said hook and adapted to rest with its pointed free end upon the rear end of said hook, thereby forming an eye therewith; said third shank having a recessed portion between the

latch finger and the handle to provide an open space between said needle and the third shank, said three shanks constituting a unit firmly cemented in said handle.

3. A mending tool for knitted fabric, comprising a handle and three forwardly protruding shanks rigidly secured therein, of which the middle shank constitutes a needle, the top shank constitutes a guard for the needle both said shanks being gradually arched parallelly inwards and each terminating with a sharp point; the third of said shanks constitutes a backwardly bent, well-rounded hook, a latch finger pivoted rearwardly of said hook and adapted to rest with its pointed free end upon the rear end of said hook, thereby forming an eye therewith; said third shank having a recessed portion between the latch finger and the handle to provide an open space between said needle and the third shank, said three shanks constituting a unit firmly cemented in said handle, and said hook and latch finger being displaced slightly sideways to said needle and guard.
